UNITED STATES PATENT OFFICE

WILLIAM L. TAYLOR, OF CINCINNATI, OHIO

MULTIPLEX BAG

Application filed June 17, 1927. Serial No. 199,540.

My invention relates to an improved means of making bags and more particularly to duplex bags in which a novel construction of the inner ply or liner blank and outer ply or cover blank form important parts of the finished bag.

My invention is especially adapted for use in the manufacture of duplex or lined bags, usually employed for packing and shipping merchandise, such, for instance, as smoking and chewing tobacco, it being necessary that packages containing this class of goods be made, not only from air and moisture-proof material, but also after the bag has been filled with tobacco and closed, it has recently been desired to entirely surround or cover said filled bag with an additional cover of thin wax paper, or a paper of similar moisture-proof construction. In order to efficiently apply and seal said additional cover of thin moisture-proof paper upon the filled and closed bag by the tobacco manufacturer's packing equipment, it is essential that the bag be of perfect form and that the "ears" at the bottom of the bag be of limber or flexible construction, whereas heretofore the flexibility of said "ears" was not an important factor, nor was the trueness in shape of the bag so particular. However, the flexibility of said "ears" and the correctness of shape of said bag are very essential features when it is desired to put said additional moisture-proof cover upon said filled and closed bag by the manufacturer's present packing equipment.

The primary object of the present invention is to provide an improved inner ply or liner blank, an improved outer ply or cover blank, and improved means of making same, which entirely eliminates the objections and difficulties above referred to, and the practice of which improved means results in a better made or "squierer" shaped bag with a minimum number of cast-offs, due to the required exactness of the bags for applying said additional cover of thin moisture-proof paper by the tobacco manufacturer's packing equipment.

Further objects of my invention are to provide a multiplex bag, as above described

and for the purposes intended, which is simple, efficient, inexpensive to manufacture, and the construction of which is highly desirable for use upon packing equipment where an additional cover of thin moisture-proof paper is applied to the bag after the latter has been filled, closed and sealed by said packing equipment.

Briefly and generally stated, the invention consists in cutting away a portion of the inner ply or liner blank and outer ply or cover blank at an angle to the center transverse fold, so that the excess quantity of paper heretofore folded within the "ears" (thereby making them stiff and non-flexible) is eliminated, thus making them limber or flexible and easily handled by the manufacturer's packing equipment.

My invention further consists in the modified construction, combination, location and arrangement of parts and in the bag as an article of manufacture, as herein set forth and claimed.

In the drawings:

Fig. 1 is a plan view of the bag blank for a single bag, showing a portion of the liner folded back at one corner;

Fig. 2 is a perspective view of a bag made in accordance with my invention shown in closed and sealed position;

Fig. 3 is a bottom view thereof, clearly showing the "ears" inturned;

Fig. 4 is a sectional view taken on a plane corresponding to line 4-4 of Fig. 2 and showing one of the "ears" of the bag;

Fig. 5 is a front elevation of the bag shown in Fig. 2 previous to having the top closed and the seal applied;

Fig. 6 is a front elevational view of Fig. 2, except that the "ears" are shown turned under in close proximity to the body of said bag;

Fig. 7 is a similar view to Fig. 1, partly broken away for lack of space, and showing a modified form of the invention;

Fig. 8 represents two long superposed strips or webs of paper of different widths pasted together at intervals a shorter distance from their longitudinal edges and at certain points or spots in the center thereof;

Fig. 9 is a similar view showing by dot and dash lines the parts cut away in forming the individual bag blanks; and.

Fig. 10 is a combined view of Fig. 8 and 5 Fig. 9, respectively, showing one of the bag blanks detached, and the discarded or waste parts cut away.

In order to enable others skilled in the art to understand, practice and use said invention, I will now proceed to describe the same in detail, reference being made for this purpose to the accompanying drawings wherein I have illustrated a preferred form of blank from which the bag may be made, but I do not 15 wish to be understood as limiting myself to the particular form of blank shown, as other forms or shapes may be employed without departing from the scope or spirit of the invention.

20 In the preferred form shown, however, the duplex bag comprises an inner ply or liner 1 consisting of a thin sheet of waxed, or similar moisture-proof, paper, and an outer-ply or cover 2 consisting preferably of a heavier 25 grade of paper having great tensile strength.

The method of making the bag is substantially as follows:

A plurality of webs or plies of paper 1a and 2a respectively, are drawn in registry 30 with each other from rolls by any suitable means. Narrow layers of glue or paste 3 are applied near the respective longitudinal edges between the adjacent webs or plies of paper 1a and 2a on side 4 of the bag blank 5. Said layers of glue preferably extend from 35 end 6 to "scored"-line 7. It has been found in practice, however, that by omitting a small portion of the glue stream at 8 over the "scored"-line 9, the top closure portion of the 40 bag is more readily handled by the manufacturer's packing equipment. The plies of paper are then pressed together upon said layers of paste whereby they are permanently attached together in accurate registry with 45 each other, as shown in Fig. 8.

The next step of the operation consists in dieing out or cutting off the longitudinal strips 20 from side 4, which strips are shown in Fig. 10. The edges of side 10 are then 50 folded inwardly to form inturned securing flaps 11. A coat or layer of glue paste 11' is then applied to the exposed surface of each outer flap 11, as shown in Fig. 7. The individual bag blank 5 is then severed or cut off 55 from the webs of paper 1a and 2a. The sides 4 and 10 of said bag blank are then folded transversely on central score-line 12 and the longitudinal edges of side 4 of the bag are then pressed down upon the glued faces 11' 60 of the flaps 11 whereby the bag is completed and issued from the bag machine in a "flat" form.

To prevent the liner from bulging or separating from the cover at the top of the bag 65 when the bag is opened by the manufacturer's

packing equipment previous to filling with the tobacco, I provide a spot or drop of glue 13 between said cover and liner, as clearly shown in Figs. 1, 8 and 10, respectively.

The inside ply or liner is permanently fastened to the outer ply or cover by this method of construction, to prevent shifting or withdrawal thereof, which is a decided advantage, particularly on account of the easy and simple manner in which it is mechanically 70 accomplished. The plies 1a and 2a being glued together at the first step of the operation are held in absolute and accurate registry with each other during the subsequent operations, thereby preventing any shifting 75 of the plies relative to each other, as is the case where the plies are glued together after the dieing out operation.

Two or more complete rolls of paper can be glued together, as shown in Fig. 8, on a 80 separate machine before making it up into bags ready for printing and this can be done on a very simple combining and rewinding machine. In other words, the plies of paper 85 can be unwound from separate rolls and 90 glued together at the necessary points and then rewound upon a single roll for manufacture into bags on simple bag making machinery, such as is used for making bags of 95 single ply material. In doing this, all that 100 is required is to mark or cut into the paper an identifying mark to show the register point for the dieing out knives of the bag making machine. In this way, if desired, the gluing together of the sheets (as shown in Fig. 8) could be done by one organization or 105 factory and the dieing out and completing of the bag (as shown in Fig. 10) could be done by another organization or factory, so that if 110 the sheets are glued together the material 115 can be handled as if it were a single piece of paper instead of a plurality of sheets of paper. This is a decided advantage in the construction of the bag, since it enables the bag to be constructed more readily and economically by the use of simple, instead of 120 complicated, machinery.

The inturned flaps of the inner and outer plies being glued together form a stronger and more substantial construction than otherwise.

The chief advantage of this invention is that the dieing out knives of the bag making machine cut the longitudinal strips 20 on an angle or bias 14 from the central fold or "score"-line 12 to the "score"-line 15, as clearly shown in Figs. 1, 9 and 10, respectively.

A bag blank cut in this manner eliminates any excess paper from being folded within the ears 16 of the bag, when formed ready 125 for receiving its contents. With this construction the ears 16 are readily folded on lines 17 (to the position illustrated in Figs. 3 and 6, respectively) by the manufacturer's 130 packing machines and are flexible, thereby

permitting said additional covering of moisture-proof paper to be easily applied or put on after the bag has been formed, filled and closed by the manufacturer's packing machinery.

While I have set forth a particular construction and method, it will be understood that this is merely by way of illustration and that the invention is capable of modification

10 without material departure from its scope or spirit as defined in the claims, as, for instance, as shown in Fig. 7, the inner ply or liner 1 may be provided with cuts or slits 18 and 19 which will further aid in producing 15 a bag of the character described, so that the ears 16 will not be held in open position, as shown in Fig. 2, but will readily assume a position as shown in Figs. 3 and 6, respectively.

20 What I claim as new and desire to secure by Letters Patent is:

1. As an article of manufacture, a tobacco bag, the blank of which is folded intermediate its ends, one side of the blank being 25 narrower than the other side, a transverse score-line provided on the wider side the longitudinal edges of the wider side being inturned to form securing flaps, a portion of each flap being cut away on a line extending 30 from said score-line to said fold and said flaps being adhesively secured to the longitudinal edges of the narrow side of the blank.

2. As an article of manufacture, a bag, the blank of which is folded intermediate its 25 ends, one side of the blank being narrower than the other side, the longitudinal edges of the wider side being inturned to form securing flaps, a score-line provided on the wider side and extending parallel with and 40 spaced apart from said intermediate fold, said flaps being cut away on a line extending from said intermediate fold to said score-line and secured to the longitudinal edges of the narrow side of the blank.

25 3. As an article of manufacture, a tobacco bag, the blank of which is centrally folded intermediate its ends and narrower on one side of the central fold than on the other side, the wider side being provided with a 50 transverse score-line extending parallel with and spaced apart from said central fold, the longitudinal edges of the wider side being inturned to form securing flaps, which flaps are characterized by the fact that a substantial portion thereof is cut away approximately on a line extending from said central fold to said score-line and said flaps being adhesively secured to the longitudinal edges of the narrower side of the blank.

55 4. As an article of manufacture, a tobacco bag, the blank of which is folded between its ends, the blank on one side of the fold being narrower than the other side, the longitudinal edges of the wider side being inturned to 60 form securing flaps, a score-line provided on

the wider side of the blank and extending parallel with and spaced apart from said intermediate fold, the inner ends of said flaps being substantially cut away on an angle of approximately 45° or a line extending from 70 said intermediate fold to said score-line, said flaps being also secured to the longitudinal edges of the narrow side of the blank.
